UNITED STATES PATENT OFFICE.

FREDRICH STOCKER, OF HIGHLAND, ILLINOIS, ASSIGNOR TO STOCKER CONCRETE MATERIAL WASHER COMPANY, OF HIGHLAND, ILLINOIS, A CORPORATION.

WASHING APPARATUS.

966,869.

Specification of Letters Patent.

Patented Aug. 9, 1910.

Application filed May 18, 1910. Serial No. 561,942.

To all whom it may concern:

Be it known that I, FREDRICH STOCKER, a citizen of the United States of America, residing at Highland, in the county of Madison and State of Illinois, have invented certain new and useful Improvements in Washing Apparatus, of which the following is a full, clear, and exact description, reference being had to the accompanying drawings, 10 forming part of this specification.

My invention relates to apparatuses for use in washing sand and other materials, the apparatus forming the subject matter of the present invention being of the type shown 15 in Patent No. 888,766, issued to me May 26, 1908.

The object of my present invention is to so construct a washing apparatus of the kind referred to as to provide for the material being washed, it being retained in the apparatus for a greater or less period, according to whether it requires a large amount of washing action, or a lesser amount of washing action in cleansing it.

25 A further object of the present invention is to so construct the flights in the apparatus as to provide for their performing their offices more efficiently.

Figure I is a vertical longitudinal section 30 through my apparatus. Fig. II is a top or plan view of the apparatus, the drum being partly broken out, and the end frames being shown in horizontal section. Fig. III is an enlarged cross section of the drum, the material conducting chutes therein, and the means for adjusting these chutes. Fig. IV is a perspective view of one of the handles of the chute adjusting means and the keeper member in which said handle is arranged.

40 In the accompanying drawings:—1 designates a drum that is revolvably mounted in end frames 2 and for the support of which rollers 3 are preferably provided. Any suitable means may be made use of for revolving said drum, the means shown comprising a sprocket ring 4 encircling the drum at one end, a driving chain 5 in engagement with said sprocket ring, and shafts 6 and 7 connected by gearing 8 through the medium of 45 which power is communicated to said driving chain.

9 designates hanger bars arranged parallel with each other and supported by the end frames 2 of my apparatus. These supporting bars extend longitudinally through

the drum 1 and at the end of the drum provided with a receiving opening for the material to be washed, the bars serve to support a feed chute or hopper 10. This feed chute is preferably immovably attached to the 60 supporting bars, and there is preferably also immovably attached to said supporting bars, adjacent to the feed chute but located within the drum, a chute 11 that is inclined downwardly and forwardly from the inlet 65 of the drum. At the opposite end of the apparatus, or that provided with the outlet opening 1^b through which the material that has been washed is discharged, is a discharge chute 12, immovably attached to the supporting bars 9 and projecting through the outlet opening. There is also preferably a chute 13, located back of the discharge chute 12 and which is immovably supported by the bars 9. 70

14 is a water conveying pipe through which water is delivered to the drum 1 at its discharge end to circulate from this discharge end toward the receiving end of the drum. No invention *per se* is herein claimed 80 for the parts thus far specifically described, inasmuch as they correspond closely to parts in my previous patent, hereinbefore mentioned.

15 designates chutes arranged in series 85 throughout the central portion of my apparatus within the drum 1 and which are pivotally connected at 16 to the parallel hanger bars 9, thereby providing for said chutes being inclined forwardly toward the delivery end of the drum in any desired degree and adjusted either forwardly or backwardly in order that the material deposited therein may, upon riding downwardly in the chutes, be advanced toward the delivery end 90 of the drum more or less quickly as it is picked up by the drum, through the medium of its flights 17 and emptied into the chutes during the forward movement of the material. To provide for the movement of the 100 chutes 15 in alternate series upon their pivots, each alternate pivotally mounted chute has connected to it a shift bar 18 at one side thereof and the intervening chutes having connected to them a shift bar 19 at the 105 other side thereof. Each of said shift bars is operated through the medium of a handle bar 20 that is pivoted to the shift bar and is provided at its outer end with a handle 21 and in which are notches 22. The 110

handle bars 20 extend through slots 23 in keeper bars 24 supported by the end frames of the apparatus and which preferably also serve as supports for the hanger bars 9.

5 In the practical use of my apparatus, the pivotally mounted chutes 15 may be all disposed as they are shown in the drawings, so that the material delivered to them by being picked up by the flights 17 during 10 revolution of the drum 1 will be gradually advanced from one chute to the next, as contemplated in my previous Patent No. 888,766, until the material is finally discharged in a clean condition through the 15 discharge chute 12. In washing very dirty material, it is necessary in order that the cleansing action may be perfect to retain the material in the drum of the apparatus for a greater period of time and dump it a 20 greater number of times into the chutes 15 after it is lifted out of the water in the drum by the flights; and, in such instances, the chutes 15, either all of them or part of them, are swung backwardly toward perpendicular lines passing through their pivots. Thus, for illustration, if the material 25 that is being washed contains a very large per cent. of dirt, the entire number of pivotally mounted chutes 15 are swung backwardly by the actuation of the shift bars 18 and 19 through the medium of the handle bars 20, so that the material as it is emptied 30 into the chutes and descends therein will not approach the discharge end of the drum as rapidly as it would if the chutes were arranged as they are shown in the drawings and would, therefore, be subjected to a longer washing operation. In the event 35 that it is desired to subject the material to a washing operation consuming a period of time greater than that required when the chutes are arranged as shown in the drawings and less than that when all the chutes are in nearly perpendicular positions one set 40 of chutes will be swung into nearly vertical positions and the other chutes be allowed to remain in the positions shown in the draw- 45

ings. In this event, the material will advance more rapidly upon one set of the chutes 15 than it does upon the other set of chutes. 50

An important feature in my present apparatus is the construction of the flights 17 in such manner that they will more effectively control the water and the material introduced into the apparatus, with the result of accomplishing more efficient washing action upon the material that is being treated. Each of the flights 17 is curved abruptly near the receiving end of the drum 1, as seen at 17^a, the curves at the points 55 mentioned being so located as to provide for the material delivered into the drum at the receiving end being picked up by the flights in a manner to direct it forwardly from the forward ends of the flights and into the 60 chutes nearest the receiving end of the apparatus, instead of any of such material being permitted to move backwardly along the flights toward the receiving end of the drum instead of being properly deposited in the 65 chutes that should receive it.

I claim:—

1. In a washing apparatus, a revoluble drum, hanger bars in said drum, a series of chutes pivoted to said hanger bars, means 75 for swinging a series of said chutes alternating with intervening ones, and a second means for swinging a series of intervening chutes.

2. In a washing apparatus, a revoluble 80 drum, hanger bars in said drum, a series of chutes pivoted to said hanger bars, means for swinging a series of said chutes alternating with intervening ones, and a second means for swinging a series of intervening 85 chutes; said means comprising a shift bar having pivoted connection with one series of chutes, and a second shift bar having pivoted connection with the other series of chutes.

FREDRICH STOCKER.

In the presence of—

LOUIS BLATTNER,
LOUIS O. KUHNEN.
